The ornamental design for a coffee bean dispenser, as shown and described.

DESCRIPTION

The subject matter illustrated in broken lines is illustrative only and forms no part of the claimed design.

FIG. 1 is a perspective view of a group of coffee bean dispenser showing my new design;

FIG. 2 is a front elevational view thereof;

FIG. 3 is a right side elevational view thereof, the left side elevational view being substantially a mirror image thereof;

FIG. 4 is a rear elevational view thereof;

FIG. 5 is a top plan view thereof; and,

FIG. 6 is a bottom plan view thereof.
